CANT-HOOK

Juraj Andrejchak, Duquesne, Pa.

Application November 24, 1936, Serial No. 112,583

1 Claim. (Cl. 294—17)

This invention relates to cant-hooks, one of the objects being to turn rectangular steel work, such as blooms, without subjecting the worker to undue inconvenience and injury.

A specific example of a cant-hook embodying the features of the present invention is illustrated by the accompanying drawing, in which:

Figure 1 is a side view and Figures 2 and 3 are sections taken from the lines II—II and III—III in Figure 1.

This cant-hook includes a lever 1 having an angularly extending pointed end 2, and a right angular cant-hook 3 pivoted to the lever 1 adjacent the end 2 to swing in the direction the latter extends. The cant-hook 3 has a bifurcated portion 4 that straddles the lever 1, a bolt 5 being passed through registering holes in the lever 1 and this portion 4 to provide the required pivotal connection. The inner end surface 6 of the bifurcated portion 4 is arranged to provide abutments against which the lever 1 strikes when the parts pivot in either direction, this arrangement providing a means for limiting the swing of the cant-hook 3 in both directions from its normally operative position. The cant-hook 3 is right angular in shape so that its end fits a right angular bloom, the cant-hook operating in the usual fashion excepting that the working face of the cant-hook is parallel the work canted while the end 2 serves to dig into the opposite side.

To prevent slipping of the working face of the cant-hook 3, gripping elements in the form

of metal inserts 7 extend from this face. These elements are made of metal that is harder than the metal of the work to be canted. Due to the fact that they do not actually hook into it in their engagement with the work, they cannot retard quick release of the cant-hook. These gripping elements prevent inconvenience and accidents due to the fact that they prevent the cant-hook from slipping from the work but at the same time, as just mentioned, they do not retard quick releaseal.

I claim:

A cant-hook for canting rectangular metal work comprising a lever having an angularly extending pointed end, a right angular cant-hook pivoted to said lever adjacent said end, gripping elements extending from the working face of said cant-hook, said pointed end of said lever extending generally toward said working face of said cant-hook in opposing relation thereto and in opposing relation to said gripping elements extending from said working face of said cant-hook, and means for limiting the swing of said cant-hook in both directions from its normally operative position, said elements being made of harder material than the work to be canted and said working face of said cant-hook functioning solely through said elements when held parallel to a side of the work by engagement of said pointed lever end with an opposite side of the work and upon levering of said lever in the proper direction.
